(57) **CLAIM**

The ornamental design for a mop holder for cleaning robot as shown and described.

DESCRIPTION

Mop holder for cleaning robot

1.1 is a front view of a mop holder for cleaning robot showing a first embodiment of our new design;

1.2 is a rear view thereof;

1.3 is a left view thereof;

1.4 is a right view thereof;

1.5 is a top view thereof;

1.6 is a bottom view thereof;

1.7 is a perspective view thereof;

1.8 is another perspective view thereof;

2.1 is a front view of a mop holder for cleaning robot showing a second embodiment of our new design;

2.2 is a rear view thereof;

2.3 is a left view thereof;

2.4 is a right view thereof;

(Continued)

- 2.5** is a top view thereof;
2.6 is a bottom view thereof;
2.7 is a perspective view thereof; and
2.8 is another perspective view thereof.

1 Claim, 12 Drawing Sheets
